MOBILE TELEVISION AND PROJECTION DISPLAY VEHICLE

Myer Apfelbaum, 2757 N. 5th St., Philadelphia 33, Pa.

Filed Oct. 23, 1963, Ser. No. 77,124

Term of patent 14 years

(Cl. D14—3)

Fig. 1

Fig. 2

FIGURE 1 is a front perspective view of the mobile television and projection display vehicle showing my novel design; and

FIGURE 2 is a rear perspective view thereof.

The dominant features of my design reside in the portions shown in full lines.

I claim:

The ornamental design for a mobile television and projection display vehicle, substantially as shown and described.
